AUTOMATIC SWITCH

Application filed March 16, 1931, Serial No. 523,183, and in Great Britain March 31, 1930.

The present invention relates to selecting switches in automatic or semi-automatic telephone systems and more particularly to switches which search for a free outlet in a 5 number of levels in succession.

Arrangements are known in which a selector having searched all the outlets in a level is stepped to the next level and continues its 10 search over outlets in this level, search over successive levels continuing until a free outlet or the last outlet of the group of outlets is reached. In such a selector the last outlet in the last level that the switch is able to search, i. e. the uppermost level in a two-motion 15 selector of a kind commonly used in automatic telephone systems, must constitute the last outlet of a group extending to that outlet. If the selector is a P. B. X. final selector and a 20 group of P. B. X. lines commences in an upper level of the selector a limit is thus placed on the number of lines the group can accommodate without change of the subscriber's directory number.

According to one feature of the present invention a selector is provided in which the 25 size of a group of outlets is not restricted (owing to the position in the bank in which the first outlet of the group is connected) by virtue of the selector wipers reaching a limiting position without searching all possible 30 outlets.

According to another feature of the invention a two-motion selector is provided having a group of outlets connected in several levels 35 with means whereby, having searched over a level or successive levels containing outlets of the group and reaching the limiting position, the selector wipers are released to a normal position and are then stepped to the first level of the switch bank and searching continues over this and successive levels if 40 there are any until a free outlet or the last outlet of the group is reached.

The invention is particularly applicable to 45 P. B. X. final selectors serving large groups of P. B. X. lines as it enables a large group of lines which commences in one of the upper levels of the bank to be extended beyond the last contact of the uppermost level by utilizing 50 vacant lower levels and so avoiding a

change in the directory number of the P. B. X. In the case of large and important private branch exchanges this is particularly desirable and if necessary the number of a small exchange may be changed in order to accommodate an extension to the more important 55 exchange.

Large groups of outlets are generally connected to selectors employing more than one set of wipers and associated contact banks 60 and in the case of final selectors one method of operation is to search over the outlets in a level available to one set of wipers and, if no free outlet is found, search over the outlets in the same level available to another set of 65 wipers is made, search over the several sets of outlets in successive levels continuing until a free outlet or the last outlet of the group is reached.

It is usually arranged that a P. B. X. final 70 selector connecting with large groups of lines responds to the "tens" digit to step the wipers to the level containing the first line in the group, the selector thereafter stepping automatically, the "units" digit being absorbed. 75

If, in the course of search, the last contact in a level is reached, a relay may be operated over this contact to effect the release of the switch as regards its searching motion and by the provision of normal post 80 contacts, complete release to a normal position may be effected from which position the switch is stepped to the first level, containing further contacts of the group over which it proceeds to search in the same manner 85 as over the upper levels, the search being continued if necessary over a number of levels.

Although the application of the invention 90 has been described with reference to a switch of the type in which the grouped contacts are arranged in horizontal levels vertically disposed, the switch wipers being stepped vertically to a desired level and thereafter stepped over the level, it will be appreciated 95 that it may equally be applied to any two-motion selecting switch. In this connection it will be realized that the terms upper and lower levels refer to the groups of contacts engaged by the selector in its second motion 100.

remote from and near to respectively the normal position of the wipers, the first level being the group of contacts nearest to the normal position of the wipers.

5 The accompanying drawings comprising Figs. 1 and 2 when placed together with the corresponding lines in alignment illustrate by way of example the application of the invention to a final selector for dealing with 10 large groups of P. B. X. lines and having 20 lines in a level. The lines of a group may extend over more than one level, over which levels successive search for a free line is made. If it is desired to increase the number 15 of lines in a group without disturbing the numbering scheme, and the levels above those already occupied by the group are occupied by another group or the group to be enlarged already extends to the limiting position 20 of the switch, the overflow lines to be provided are accordingly accommodated in the first level and may be succeeding levels assuming these to be vacant.

Normal post contact np are provided opposite the last level containing lines of the group before extension the operation of which prepares circuits for the release of the switch shaft to its normal position and its re-stepping to the first level over which the 30 search for a free line continues if all the lines in the original part of the group are busy. The whole of the switch outlets may be taken up by a single group of lines in which case continuous search may be effected. The first 35 line of a group is reached by dialling the tens digit of the first line of the group which steps the switch to a level in accordance with the digit dialled and over which and successive levels search takes place. For this purpose the connections marked X are made. If all the outlets of a switch form one large group the switch may be arranged to search continuously, commencing at the first level, by substituting the connections shown in 40 dotted lines and marked Y for those marked X.

In the P. B. X. final selector shown there are two sets of wipers, each being concerned with a separate set of bank contacts. Search 50 is made first over one set of contacts by the appropriate wipers and then over the other set of contacts with the other set of wipers. The last contacts in a level are therefore the last contacts of the second set of contacts. A 55 last contact of the first set of each level is connected to a relay which when operated causes the switch to release to rotary normal, whereupon the second set of wipers is connected in circuit and search over the second 60 set of contacts in the level proceeds.

In the drawings A indicates the impulse relay; B the release relay; D the answering supervisory relay; C the dialling relay; H the test relay; F the ring cut-off relay.

65 Relay RN is concerned with the release as

regards the rotary search. Two sets of contact banks are shown, one having associated speaking wire wipers A, B and test wiper C, the other having corresponding wipers A1, B1, C1. Contacts over which a first search is made are associated with wipers A, B and C. Relay E operates when a first search has been unsuccessfully made to connect the circuits to the second set of wipers A1, B1, C1. VS is a relay concerned with the re-stepping of the wipers to a succeeding level.

The vertical, rotary and release magnets are designated VM, RM and ZM, respectively.

70 RZM is a magnet which operates to release the wiper shaft only as regards rotary motion. Contact zm is opened when release magnet ZM operates. Contact rm is closed when the rotary magnet operates.

75 Contacts $n1$, $n2$, $n3$ are vertical off-normal contacts shown in the unoperated position. Contacts $nr1$ and $nr2$ are rotary off-normal contacts also shown unoperated. Contact $s1$ operates on the eleventh rotary step being made. Contact np is a normal post contact provided to be operated when the wiper shaft reaches a level containing the last contact of a group in an upper level and after search over this level it is required to release and re-step to the first level.

80 Relay RN is connected to the last, i. e. eleventh contacts of the bank associated with wiper A. Relay DR is connected to the eleventh contacts of the banks associated with wipers C and C1.

85 Eleventh contacts in the bank of wiper B1 of levels in which last lines of P. B. X. groups appear are connected to a wire in the final selector multiple and this wire is earthed at one point thereby enabling variations in the 90 number of levels in a group to be made readily.

95 The selector is found disengaged by reason of the incoming test wire c being unearthing. On the test relay of the preceding selector operating the speaking wires thereof are switched through and relay A operates in a 100 circuit from battery over its coil (II), contacts zm, d2 the b wire, the preceding loop, wire a , contact d1, coil (I) to earth.

105 At front contact a1 a circuit is made for release relay B and relay C, the circuit of relay C including its coil (I) and contact n1.

110 Relay B operates, earthing the incoming c wire at contact b1, opens a point in the release magnet circuit at back contact b2, prepares the circuit of the magnets RM and RZM at front contact b2, and that of magnet VM at b5.

115 Relay C further prepares a circuit for magnet VM at contact c2 and opens a point in the rotary magnet circuit at contact c1.

120 Relay A receives impulses in due course and on its first release the circuit of magnet VM is made over contacts a1, dr2, b5, c2, coil 125

130

(II) of relay C. The magnet steps the wiper shaft and contact $n1$ opening leaves relay C dependent on contact $a1$ for its continued operation.

5 When the train of impulses is completed relay C releases as relay A is steadily energized.

On release of relay C a circuit is made for coil (I) of relay DR over contacts $n2$, $h4$, 10 $b2$ and $c1$. Relay DR operates, disconnects magnet VM at contact $dr2$ and connects rotary magnet RM over contacts $vs2$, $rn2$, $dr1$, $c1$, $b2$, $h4$ and $n2$ to earth. The magnet operates and steps the wipers into the bank; 15 only wipers A, B and C however, are in circuit.

If the first line is free test relay H operates in a circuit from earth over contacts $h4$, $rn1$, coil (I) of relay H, contact $e4$, wiper C, the 20 cut-off relay of the preselector of the called line and battery. Relay H operates and locks up in a circuit over its coil (II), contacts $rn3$, $b3$, $h4$ and $n2$. Contact $h1$ closes somewhat later than contact $h4$ and marks the called 25 line engaged. At contact $h4$ also the circuit of magnet RM is opened and the wipers remain on the first contact. Subsequent operations will be referred to later.

If the first line is engaged relay H fails to 30 operate. Contact rn makes a circuit for coil (I) of relay C. The relay operates and opens the circuit of magnet RM at contact $c1$. The magnet armature retracts and opens the circuit of relay C at contact rn . Relay C releases and the magnet circuit is re-made at contact $c1$.

The wipers are now stepped onto the second contacts. If those be free relay H operates, if not, the interaction of relay C and magnet 40 RM continues.

If all the lines traversed by wipers A, B and C are engaged the wipers are eventually stepped onto the eleventh contacts. Here contact $s1$ operates but has no function at this 45 stage. However, a circuit is made for relay H over contacts $b4$, $rn1$, relay coil, contact $e4$, wiper C, the eleventh contact and coil (II) of relay DR.

50 Relay H operates opening the rotary magnet circuit at $h4$ and the circuit of coil (I) of relay DR, but this relay is now held over its coil (II).

55 Relay RN then operates from battery connected to wire RR, over contacts $f2$, $h2$, $e2$, wiper A, coil (I) of relay RN, contact $n3$ to earth. It locks up in a circuit over contacts $b4$, $rn1$, $nr1$ and coil (II) of the relay, and opens the circuit of coil (I) of relay H at contact $rn1$ and that of coil (II) at contact 60 $rn3$ and relay H releases. The circuit of the rotary release magnet RZM is now completed as follows: earth, contacts $n2$, $h4$, $b2$, $c1$, $dr1$, $rn2$, $f6$, magnet RZM to battery. The magnet operates and the wipers are restored to the 65 rotary normal position whereupon contact

$nr1$ is restored. This breaks the holding circuit of relay RN but before this releases, relay E operates in a circuit over back contacts $vs3$ and $nr1$, front contact $rn1$ and contact $b4$ and locks up over contacts $vs3$, $e1$ and $n3$. At 70 front contacts $e2$, $e3$ and $e4$ wipers A1, B1 and C1 are connected in place of wipers A, B and C.

On the release of relay RN the circuit of magnet RZM is opened and the circuit of the rotary magnet RM is closed at contact $rn2$. The wipers are then stepped into the bank and search takes place over the second set of contacts in the manner before described.

If all the lines connected in this level are 80 busy the wipers are stepped on to the eleventh contacts and if the group extends to the next succeeding level contact $s1$ is operated but has no function at this stage. Relay H operates over contacts $b4$, $rn1$, its coil (I), contact $e4$, 85 wiper C1 and eleventh bank contact and coil (II) of relay DR. Contact $h4$ opens the rotary magnet circuit and the circuit of coil (I) of relay DR, but this relay is now held over its coil (II).

90 Relay VS operates in a circuit from battery over contacts $f2$, $h2$, $e2$, wiper A1, coil (I) of the relay, contact $n3$ to earth and at contact $vs3$ releases relay E. When relay E releases the circuit of coil (I) of relay VS is opened but this relay being slow to release continues to maintain its contacts operated. Relay RN now operates as in the case of unsuccessful search over the first set of contacts and releases relay H at contacts $rn1$ and $rn3$. Relay H releasing, a holding circuit is closed for relay VS over its coil (II), contacts $vs1$, $rn2$, $dr1$, $c1$, $b2$, $h4$ and $n2$ and the rotary release magnet RZM operates in parallel with coil (II) of relay VS. The wipers are 95 restored to their rotary normal position and the holding circuit of relay RN is opened at contact $nr1$. Relay RN releases disconnecting magnet RZM and completing a circuit for the vertical magnet. The circuit is as follows: battery over magnet VM, front contact $vs2$, back contact $rn2$, contacts $dr1$, $c1$, $b2$, $h4$ and $n2$ to earth and the wipers are given one vertical step. The holding circuit 100 of relay VS is opened at contact $rn2$ and on that relay releasing and contact $vs2$ falling back the wipers are stepped on to the first contacts in the level, the rotary magnet operating over back contact $vs2$ and the circuit previously traced. Search then proceeds in the manner already described over the first set of contacts of the new level to which the switch has been raised.

110 Assuming that the group has been extended to the first level then when the outlets of all the levels containing lines of the original group have been tested and found engaged, the wipers, A1, B1, C1 reach a limiting position and are stepped to the eleventh contacts of the bank. When the wipers reached the 115 120 125 130

level containing the last of said outlets the normal post contacts np operated. Relay H operates in series with relay DR in the following circuit: Earth, contacts $b4$, $rn1$, coil (I) of relay H, contact $e4$, wiper C1 and its eleventh contact, coil (II) of relay DR to battery. The rotary magnet circuit is opened at $h4$ and search ceases, and relay DR is now held over its coil (II). Relay VS operates in the circuit from earth over $n3$, coil (I) of relay VS, eleventh contact in bank of wiper A1, and this wiper, contacts $e2$, $h2$, $f2$, to battery on the wire RR. Relay E now releases since its holding circuit is opened at $vs3$, and completes an operating circuit for relay RN, from earth over $n3$, coil (I) of relay RN, eleventh contact and wiper A, contacts $e2$, $h2$, $f2$ to battery on wire RR. At contact $rn1$, a holding circuit is closed for its coil (II), and at $rn4$ it opens a short circuit across the coil (II) of relay F. Relay F now operates in a circuit from earth over contact $rn3$, coil (II), to battery, since contacts np , and $vs5$ are also open. At contact $f1$ provision is made to prevent a short circuit being placed across coil (II) of relay F when the switch is released and np closes, and at $f5$ a holding circuit for coil (II) of relay RN is closed depending upon $n3$. At $f6$ a circuit is prepared for the release magnet ZM.

On the operation of RN relay H releases since the circuits for the two coils (I), (II) are opened at $rn1$ and $rn3$ respectively. At $h4$ the circuit for the release magnet ZM is closed and this magnet operates releasing the switch to normal. The circuit for ZM is as follows: Earth over contacts $n2$ and $vs6$, $h4$, $b2$, $c1$, $dr1$, $rn2$, $f6$, winding of ZM to battery.

40 The switch wiper shaft is released to normal and the vertical and rotary off-normal contacts are restored. Relay RN releases owing to its circuit being opened at $rn1$. At $rn2$ a circuit is completed for the vertical magnet VM as follows: Earth over contact $vs6$, contacts $h4$, $b2$, $c1$, $dr1$, $rn2$, $vs2$ winding of vertical magnet VM to battery, and the wipers are stepped up to the first level. At contact $rn2$ also the circuit of relay VS is opened and at $rn3$ the circuit of relay F is opened, these two relays releasing. At $vs2$ a circuit for the rotary magnet RM is completed and the wipers are rotated on to the first contact, when, if this is engaged, search is over the level takes place until a free contact is found. If no free contact is encountered and further lines of the group are connected in the next level the wipers are released to rotary normal and stepped up to the next level where the search is continued as described above.

When, during the search over the first or second set of contacts of a level, a free line is found, relay H operates and locks up and disconnects the rotary magnet as before-

mentioned. The speaking wires are switched through by contacts $h2$ and $h3$ and contact $h1$ connects the busying earth to the test wiper in use. Relay DR releases shortly after contact $h4$ changes over and at contact $dr3$ a circuit is made from the ringing generator over the coil (I) of ring tripping relay F, contacts $dr3$, $f3$, $h3$, $e3$, the called line, contacts $e2$, $h2$, $f2$ to battery. The subscriber's line is rung, ringing tone being fed to the calling line during ringing from wire RS over contacts $dr4$, $f4$, $bc3$ and $h5$ and is cut off when the relay F operates.

When the called subscriber replies relay F operates over the called subscriber's loop, and at $f2$ and $f3$ switches the calling subscriber through and completes the circuit for relay D. Relay F locks up over its coil (II) in parallel with coil (II) of relay H, over contacts $b3$, $h4$, $n2$, the contact $f1$ opening the short circuit across coil (II) of relay F. Relay D operates and reverses the connection of relay A to the incoming speaking wires at contacts $d1$ and $d2$ to give the answering supervisory signal.

If all the lines of the group are busy, stepping continues until the eleventh contact in the level in which the last line of the group of P. B. X. lines is situated is reached. Prior to reaching the eleventh contacts the shaft contacts $s1$ are operated and relay H operates as for a free line. The eleventh contact of this level in the bank of wiper B1 being earthed, relay BC operates over contacts $e5$, $s1$, $dr3$, $f3$, $h3$, $e3$, wiper B1 and eleventh bank contact to earth. Relay RN does not operate as there is no connection over wiper A. Relay VS operates over wiper A1 and although contact $vs3$ is operated relay E is held by contact $bc1$. Lamp flash current and busy tone are fed alternately from wire BB over contacts $bc3$ and $h5$ to the earthed coil of the answering supervisory relay D. In the periods during which lamp flash current is applied relay D operates and battery over coil (II) of relay A is applied to the a and b wires over contacts zm , $d1$ and contacts zm , $bc2$ and $d2$ to give the parallel battery flash signal. During the lamp flash periods relay B is held in a circuit over back contacts $a1$, $dr2$ and $d3$, relay A being released during these periods.

A congestion meter may be connected to the eleventh contact of the level in which the last line of the group appears. In this case relay BC operates to earth connected to the last contact in the level in the bank of wiper B1 and on the operation of contact $bc1$ a circuit is closed over contact $vs3$ and wiper B for the meter which is connected to the last contact in the level in the bank of wiper B.

The release of the selector is controlled by relay A. When the incoming loop is opened relay A releases followed by relay B. At contact $b1$ earth is disconnected from the c wire to release preceding switches. At contacts

70

125

130

b3 and b4 points in the circuits of both coils of relay H are opened.

Relay H definitely releases, disconnects the wiper set in use at contacts h2 and h3 and the circuit of release magnet ZM is closed at contact h4. The magnet operates and the selector returns to normal, whereupon the opening of contact n2 results in the de-energization of the magnet. Contact n3 on opening causes release of relay E if this has been operated.

During the time magnet ZM is operated coil (II) of relay A is disconnected from the line to prevent operation if the selector is seized whilst returning to normal.

If there is a single large group of lines connected to the final selector and occupying all the levels the connections Y may be substituted for those marked X and the switch 20 will in this case commence search in the first level irrespective of the digit dialled.

The operation in this case is as follows: When the selector is picked up relays A, B and C operate as before. When the first impulse is dialled relay A releases and closes the circuit of the vertical magnet which steps the wipers on to the first level. The vertical off-normal contacts are operated and on the re-operation of relay A at the end of the impulse a connection is made over the front of contacts a1 and n1, unoperated rotary rotary off-normal contact nr2 for coil (II) of relay DR. Relay DR operates and at contact dr2 opens the vertical magnet circuit 30 thereby preventing the remainder of the dialled impulses from taking effect.

A circuit is now closed from earth over contacts n2, h4, b2 dotted line connection, contact dr1, coil (I) of relay DR to battery. 40 and when relay C releases this earth is extended over contact c1, dotted line connection, contacts rn2, vs2, rotary magnet RM to battery. The rotary magnet operates and steps the wipers into the bank and towards the end of its armature stroke closes contact rm and operates relay C. Contact nr2 opens when the first step has been taken and coil (II) of relay DR is deenergized, the relay 45 depending then for its energization on its coil (I). The rotary magnet and relay C interact to effect search over the level as before and search over successive levels takes place until if no free line is found the last line is reached. Contacts np are situated in this case opposite the last level and are operated when the shaft reaches this level. If all the contacts in this level are busy the wipers are stepped to the last contacts with relay E 55 operated and relay VS operates. Coil (II) of relay DR is energized to guard against de-energization of its coil (I) with operation of relay H which operates in series with coil (II) of relay DR. Relay E releases and relays RN and F operate and the shaft is returned to normal and is re-stepped to level 60 65

one as previously described and commences a re-search over the outlets of the switch for a free line.

What I claim as new and desire to secure by Letters Patent is:

1. In a telephone system, an automatic switch, a trunk group accessible to said switch comprising two different valued sub-groups, said trunk group being assigned a number corresponding to the higher valued sub-group, means for operating said switch responsive to impulses to the higher valued sub-group, means for causing said switch to hunt over said higher valued sub-group for an idle trunk, and means operative in case no idle trunk is found in said higher valued sub-group for automatically operating said switch to the lower valued sub-group and for continuing the hunting operation over this sub-group.

2. In a telephone system, an automatic switch, a trunk group accessible to said switch comprising two different valued sub-groups, said trunk group being assigned a number corresponding to the higher valued sub-group, means responsive to received digit impulses corresponding to the number assigned to said trunk group for operating said switch past the lower valued sub-group to the higher valued sub-group and for causing it to search for an idle trunk therein, a relay operated when the last trunk in said higher valued sub-group is found busy, means controlled by said relay for restoring the switch to its normal position, and means operated when said switch reaches its normal position for operating it to the lower valued sub-group where the hunting operation is continued.

3. In a telephone system, an automatic switch having access to groups of trunks over bank contacts arranged in levels, one of said groups including a plurality of upper levels and the first or lowest level, means responsive to the operation of said switch by digit impulses to the first of the upper levels of the group for automatically causing the switch to hunt over this level and the succeeding upper levels of the group for an idle trunk, releasing means for the switch, means operated by said switch when it is operated to the last of the upper levels of the group for preparing said releasing means, means effective when said switch has hunted over said level without finding an idle trunk for operating said releasing means to return said switch to normal, and means responsive to said release for operating said switch to the first level and for causing it to hunt over this level for an idle trunk.

4. In a telephone system, an automatic switch having access to trunks over bank contacts arranged in levels, means responsive to the operation of said switch by digit impulses to a level other than the first for causing the

switch to hunt over this level and levels above until a particular limiting position is reached, said means including means for automatically stepping said switch over a level, for partially releasing the switch and operating it to the succeeding level, and for automatically stepping the switch over the succeeding level, means for completely releasing said switch when said limiting position is reached, means responsive to said release for operating said switch to the first level and for continuing the hunting operation over this level, and means responsive to the finding of an idle trunk at any time during said hunting operation for stopping said switch.

5. In a telephone system, an automatic switch having vertical and rotary movements, trunks accessible to said switch over bank contacts arranged in levels, means responsive to the operation of said switch by digit impulses to a level other than the first for causing the switch to hunt for an idle trunk in the selected level and in the levels above until a particular limiting position is reached, means effective when said limiting position is reached for releasing said switch to normal, and means responsive to said release for operating said switch to the first level and for causing it to continue its hunting operation over said first level.

6. In a telephone system, an automatic switch having vertical and rotary movements, a plurality of groups of trunks accessible to said switch in a plurality of different levels, one group including one or more upper levels and the first or lowest level, means for operating said switch in its vertical movement to one of said upper levels, means for automatically rotating said switch in search of an idle trunk, means operated when said switch reaches the limit of its rotary movement in a level not the uppermost in the group for releasing said switch in its rotary direction and for operating it to the succeeding level in which the hunting operation is continued, and means operated when said switch reaches the limit of its rotary movement in the uppermost level of the group for releasing said switch in both its rotary and vertical directions and for operating it to the first level in which the hunting operation is continued.

7. In a telephone system, an automatic switch having vertical and rotary movements, trunks accessible to said switch arranged in levels, means for directly operating said switch to one of said levels and for automatically causing said switch to hunt for an idle trunk in said level, means for causing said switch to hunt over succeeding levels, said means including means for releasing said switch in its rotary direction in case no idle trunk is found in a particular level and means responsive to said release for operating said switch to the next level and for causing it

to hunt in such level, means for completely releasing said switch to normal when a particular limiting position is reached, and means responsive to said release for operating said switch to the first level and for continuing said hunting operation.

8. In a telephone system, an automatic switch having vertical and rotary movements, two sets of wipers having access to groups of trunks over bank contacts arranged in levels, means responsive to received digit impulses for operating said switch in its vertical movement to select a particular level, means for automatically rotating said switch over said level to hunt for an idle trunk with one set of wipers, and means effective in case no idle trunk is found for rotating said switch over the same level to hunt for an idle trunk with the other set of wipers.

9. In a telephone system, an automatic switch having access to groups of trunks in different levels, two sets of wipers, means responsive to the operation of said wipers to a particular level for causing said switch to hunt for an idle trunk in said level with one set of wipers, and means effective in case all of the trunks accessible to said set of wipers in said level are busy for automatically causing said switch to hunt for an idle trunk in said level with the other set of wipers.

10. In a telephone system, an automatic switch having vertical and rotary movements, two sets of wipers each having access to a plurality of groups of trunks over bank contacts arranged in levels, means responsive to received digit impulses for operating said switch in its vertical movement to select one of said levels, means responsive to the termination of said vertical movement for automatically causing said switch to rotate over said level and hunt for an idle trunk with one of said sets of wipers, means effective in case no idle trunk is found for releasing said switch in its rotary movement, and means for automatically causing said switch to rotate over the same level and hunt for an idle trunk with the other set of wipers.

11. In a telephone system, an automatic switch having two sets of wipers, a plurality of trunks accessible to each set of wipers in each of a plurality of different levels, means responsive to the operation of said wipers to a particular level for causing said switch to hunt for an idle trunk in said level with one set of wipers, means effective in case all of the trunks in said level accessible to said wipers are busy for causing said switch to hunt for an idle trunk in said level with the other set of wipers, and means effective in case all of the trunks in said level accessible to said second set of wipers are also busy for automatically raising said wipers to the succeeding level and continuing the hunting operation in said succeeding level.

12. In a telephone system, an automatic

switch having two sets of wipers, a plurality of trunks accessible to each set of wipers in each of a plurality of different levels, means responsive to the operation of said wipers to one of said levels for causing said switch to hunt for an idle trunk in said level with one set of wipers, means effective when the switch reaches a limiting position for causing said switch to hunt for an idle trunk in the same level with the other set of wipers, and means effective in case said switch again reaches said limiting position for raising said wipers to the succeeding level and continuing the hunting operation in said succeeding level.

13. In a telephone system, an automatic switch having two sets of wipers, a plurality of trunks accessible to each set of wipers in each of a plurality of different levels, means responsive to the operation of said switch to one of said levels for causing it to hunt for an idle trunk in said level with one set of wipers, two relays operated when said wipers reach a limiting position in said level, means controlled by the first relay for returning said wipers to the beginning of the level and for again initiating the hunting movement, and means controlled by the second relay for transferring from the first to the second set of wipers so that the succeeding hunting operation takes place with the second set of wipers.

14. In a telephone system, an automatic switch having vertical and rotary movements, two sets of wipers, a plurality of trunks accessible to each set of wipers in each of a plurality of different levels, means for directly operating said switch in its vertical movement to one of said levels, means for automatically rotating said switch in said level to hunt for an idle trunk with one set of wipers, means for automatically rotating said switch in the same level to hunt for an idle trunk with the other set of wipers, means operated when said switch reaches the limit of its rotary movement for releasing it in its rotary direction, and means responsive to said release for initiating the second hunting movement in case only the first hunting operation has been completed and for operating said switch to the succeeding level in case both of said hunting operations have been completed.

In testimony whereof I affix my signature.
JAMES ERRIGAL TEES.
